CLAIM

The ornamental design for a roller-equipped wedge, substantially as shown and described.

DESCRIPTION

FIG. 1 is a top plan view of a roller-equipped wedge showing my new design;

FIG. 2 is a right side view thereof; the left side view is identical;

FIG. 3 is a front view thereof; the rear view is identical; and

FIG. 4 is a bottom view thereof.

The handle fragmentarily shown in dotted outline in FIG. 2 is shown for environmental purposes only.

Fig. 1.

Fig. 4.

Fig. 2.
